DUNDAS DICK, OF NEW YORK, N. Y., ASSIGNOR TO MARIE A. MAUGER
OF SAME PLACE.

Design No. 4,875, dated May 9, 1871.

DESIGN FOR A PACKAGE.

The Schedule referred to in these Letters Patent and making part of the same.

To all whom it may concern:

Be it known that I, DUNDAS DICK, of New York city, in the county and State of New York, have invented a new and original Design for a Package; and I do hereby declare that the following is a full, clear, and exact description thereof, which will enable others skilled in the art to make and use the same, reference being had to the accompanying drawing forming part of this specification.

The drawing represents a perspective view of my new design for a package.

This invention relates to a new manner of finishing a rectangular package by the mode of securing the wrapper, and consists in the application to the folded wrapper ends of gummed pieces of paper, which give a peculiar appearance to the back and ends of the package, besides fastening the ends of the wrapper in a sufficient manner.

A in the drawing represents a rectangular package of playing-cards, tobacco, or other goods or material.

Its covering consists of a wrapper of paper or other fabric, applied so that it forms the folds *a a* at the ends in the manner shown.

The folded ends *b* of the wrapper are secured to the back of the package by small pieces, *d d*, of fabric, which are gummed to back and ends, as shown.

These connecting-pieces *d*, which may vary in size and form, produce a peculiar effect in the appearance of the package, and make the use of a string or other means for tying the wrapper dispensable.

I claim as my invention—

The design for a package, as set forth.

DUNDAS DICK.
